UNITED STATES PATENT OFFICE.

CHARLES H. HIGBEE, OF NEW YORK, N. Y., ASSIGNOR TO ANDREW J. DAVIES, OF SAME PLACE.

COAL-OIL LAMP.

SPECIFICATION forming part of Letters Patent No. 333,521, dated January 5, 1856.

Application filed April 4, 1855. Serial No. 161,229. (No model.)

To all whom it may concern:

Be it known that I, CHARLES H. HIGBEE, a citizen of the United States, residing in the city, county, and State of New York, have invented certain new and useful Improvements in Coal-Oil Lamps, of which the following is a specification.

My invention relates to that class of oil-lamps in which annular wicks are used; and my invention consists in combining with the carrier-tube and its annular wick a separate adjustable wick, which may be drawn up as it is burned away until it is almost completely used without interfering with the usual adjustment required to vary the size of the flame.

My invention further consists in the use of a guard for facilitating the introduction of the wick and wick-carrier into the annular chamber of the lamp, and for aiding in connecting the wick and carrier together, and of a guard covering the end of the stationary wick supported by the burner, as set forth hereinafter, and as shown in the drawings, in which—

Figure 1 is a longitudinal section of a wick-carrier and wick illustrating my improvement. Fig. 2 is a section showing a modification. Fig. 3 is a vertical section through the burner and lamp-reservoir.

In order to a proper understanding of my invention I have illustrated the same in connection with a lamp-burner provided with an annular-wick receptacle having two concentric tubes, A B, the former being supported by and constituting part of the burner, and 35 termed the "wick-tube," and the latter extending through the bottom of the oil-reservoir D and constituting an air-tube, within which is supported a tubular stem, a, supporting at its upper end a flame-spreader, E. The burner 40 is provided with the usual cage and dome and with an elevating-wheel, J. The wick is carried by a wick-raising tube or carrier, which, as shown, is perforated, that the wheel J may engage therewith, so as to permit the 45 carrier-tube and its wick to be raised and lowered in the annular-wick chamber by turning the shaft to which the wheel is attached; but the carrier-tube may be imperforate and provided with a rack engaging with the wheel 50 either at the outer side or at the inner side, as is common in burners.

The wick, instead of consisting of a single

wick, as usual, is in two or more sections, f g, the section f being connected immovably to the carrier-tube K, while the section g is capable of being drawn upward and out of the said tube. 55

By the construction of the wick above described I am enabled to avoid the waste which results from the use of wicks formed in single pieces or sections, which wicks must be discarded whenever they have burned away to such an extent as to become so short that the lower ends are not immersed in the oil when the upper ends are flush with the edges 65 of the wick-tubes.

The improved wick above described is arranged in the lamp so that the stationary portion of the wick will have its lower end immersed in the oil, while the movable portion 70 of the wick extends upward to the edge of the wick-tube, and is drawn up from time to time as it burns away, such an adjustment being practicable so long as any portion of the movable section g remains in contact with the stationary section. When all that can be used is consumed, the portion of wick g which must be discarded will be much shorter than that which would have to be thrown away under ordinary circumstances. While one section 75 of the wick is thus adjustable in respect to the other for the purpose of supplying the portion burned away, both portions are simultaneously adjustable by means of the elevating-wheel or other device J, as required, in order 80 to regulate the flame.

The stationary portion of the wick may consist of a single annular wick, f, as shown in Fig. 1, in which case the adjustable portion g is arranged between the portion f and the 90 carrier-tube K; or the said stationary portion may consist of two annular wicks, f f', with the movable portion g extending between them, as shown in Fig. 2.

In order to facilitate the introduction of the 95 wick into the wick-chamber, which is sometimes a difficult operation, owing to the fraying or spreading of the fibers at the lower end of the wick, and also to secure the fixed portion of the wick to the wick-carrier, I make use of a guard, n, consisting of paper, fabric, foil, or other suitable thin flexible material, extending beneath the lower edges of the wick and carrier and upward upon both sides, as shown 100

in the drawings, and as a convenient means of securing the wick and guard together I gum the face of the said guard-strip, so that the upwardly-extending portions are securely cemented both to the wick and to the carrier-tube.

I do not here claim a guard extending around the lower edge of the wick, as this forms the subject of a separate application for Letters Patent, Serial No. 161,227, the improvement herein set forth consisting in combining such a guard with the wick-raising tube and the wick, so as to facilitate the insertion of the two together into the wick-chamber, and also serve as a means of securing the wick to the carrier.

I do not here claim, broadly, the combination, with a wick, of a guard folded round the lower edge thereof, as this constitutes the subject of my application, Serial No. 161,237.

Without limiting myself to the precise construction and arrangement of parts shown and described, I claim—

1. The combination, with an Argand lamp-burner, of a stationary feeding-wick, a burning-wick, and an adjustable carrier-tube supporting both wicks, the feeding-wick being

secured to the carrier-tube, and the burning-wick being adjustable longitudinally in respect to the stationary wick and tube, substantially as set forth. 30

2. The combination, with an Argand burner having an annular-wick receptacle open at the top, of a vertically-adjustable wick-carrying tube, a feeding-wick secured thereto, and a burning-wick supported by the tube in contact with the feeding-wick, but adjustable independently of the latter, the wicks and wick-carrying tube being detachable from the burner, substantially as described. 40

3. The combination of the wick-carrying tube, feeding-wick secured to said tube, and a burning-wick supported adjustably by the said tube, and a guard, *n*, extending around the lower edges of the tube and feeding-wick and upward within the latter, substantially as set forth. 45

In testimony whereof I have signed my name to this specification in the presence of two subscribing witnesses.

CHARLES H. HIGBEE.
